SHOE CONSTRUCTION

Joseph Sbarra, Mariners Harbor, N. Y., assignor
of one-half to Hyman Posner, New York, N. Y.

Application October 15, 1943, Serial No. 506,382

2 Claims. (Cl. 36—19.5)

This invention relates to new and useful improvements in shoes, and has more particular reference to improvements in imitation turned shoes.

The invention proposes to characterize the improved shoe by an outer sole having a rand cut out and superimposed upon its marginal edge and having a shoe upper with its marginal edge engaged between and cemented to said rand and to the cut marginal edge of said outer sole. The improved feature of this invention resides in the provision of an inner sole for said shoe which includes a sheet paper sole section of one or more layers of paper extending across and cemented on said rand and being for the purpose of shaping and assisting in holding said rand in position.

The invention also contemplates various modified forms. As a modification it is proposed to arrange the paper sole section in such a fashion that it may be readily replaced when desired.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a side elevational view of a shoe constructed in accordance with this invention.

Fig. 2 is a plan view of the outer sole of said shoe.

Fig. 3 is a side elevational view of the outer sole shown in Fig. 2.

Fig. 4 is an enlarged vertical sectional view taken on the line 4—4 of Fig. 1.

Fig. 5 is a fragmentary horizontal sectional view taken on the line 5—5 of Fig. 1.

Fig. 6 is a perspective view of the sheet paper sole section shown in Fig. 5 but illustrated turned upside down.

Fig. 7 is a fragmentary horizontal sectional view similar to Fig. 5 but illustrating a modified construction.

Fig. 8 is a fragmentary enlarged vertical sectional view taken on the line 8—8 of Fig. 7.

Fig. 9 is a perspective view of one of the sheet paper sole sections used in Figs. 7 and 8.

The imitation turned shoe, in accordance with this invention, includes an outer sole 10 (see also Figs. 2 and 3) having a rand 11 cut out along its marginal edge 11'. A shoe upper 12 has its marginal edge 13 engaged between and cemented to said rand 11 and to the cutout marginal edge 11' of said outer sole. An inner sole 14 is pro-

vided for the shoe. This inner sole 14 includes a sheet paper sole section 15 extending across and cemented on said rand 11 for shaping and assisting in holding the rand in position. Said sheet paper inner sole 15 is formed from several layers. There is a top layer 16 and a bottom layer 17. This bottom layer fits within the inner side edges of the rand 11. The sheet paper sole section 15 will assume a form when cemented within the shoe to fit the curvature of the foot.

In Figs. 7—9 a modified form of the invention is disclosed in which the shoe is provided with an inner sole 14' which includes a pair of superimposed and slightly laterally positioned paper sections 20. These sections 20 extend across the rand 11 for assisting in holding the rand in position. Fastening elements 21 and 22 are formed on said sheet paper sole sections 20 and rand 11 for releasably holding said sheet paper sole sections 20 in position. The fastening elements 21 are in the nature of tongues stamped from the material of the sheet paper sole sections 20. The fastening elements 22 are in the nature of recesses formed in the top face of the rand 11 which are adapted to receive the tongues 21 when these latter parts are pressed into the recesses, as illustrated in Fig. 8. In this form of the invention the sheet paper sole sections 20 may readily be removed when they become worn. It is merely necessary to pull them from their positions. Substitute similar paper sole sections may then be engaged in position and securely held by forcing the tongues 21 thereof into the recesses 22.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a shoe, an outer sole having a rand superimposed upon its marginal edge, a shoe upper having its marginal edge engaged between and cemented to said rand and the marginal edge of said outer sole, and an inner sole for said shoe including a pair of superimposed and slightly laterally positioned sheet paper sole sections extending across said rand for assisting in holding said rand in position, and fastening elements on said sheet paper sole sections and rand for releasably holding said sheet paper sole sections in position, said fastening elements comprising tongues cut

from said sheet paper sole sections and forced into recesses formed in the top face of said rand.

2. In a shoe, an outer sole having a rand superimposed upon its marginal edge, a shoe upper having its marginal edge engaged between and cemented to said rand and the marginal edge of said outer sole, and an inner sole for said shoe including a pair of superimposed and slightly laterally positioned sheet paper sole sections ex-

tending across said rand for assisting in holding said rand in position, and fastening elements on said sheet paper sole sections and rand for releasably holding said sheet paper sole sections in position, said fastening elements comprising tongues on one of these parts and forced into recesses on the other of these parts.

JOSEPH SBARRA.
